Inventor:
Charles Kahn
By his Attorneys,
Baldwin + Wright.

UNITED STATES PATENT OFFICE.

CHARLES KAHN, OF LONDON, ENGLAND.

ACOUSTIC INSTRUMENT.

Application filed July 15, 1921. Serial No. 484,865.

To all whom it may concern:

Be it known that I, CHARLES KAHN, a subject of the King of Great Britain, residing at 30, Charing Cross Road, London, England, have invented new and useful Improvements in Acoustic Instruments (for which I have made application in Great Britain on July 15, 1919), of which the following is a specification.

10 My invention relates to an acoustic instrument consisting of a resonator or a pair of resonators, each of which is adapted closely to fit the head and ear of the wearer. In the resonator is a tapering tube, the large 15 end of which is close to the back wall of the resonator casing.

According to my invention the small end of the tapering tube ends is connected to an angle piece to which is rotatably connected 20 a second angle piece to which is rotatably connected an ear tube. Set screws may be provided to secure the second angle piece and ear tube in any desired position, but usually such set screws are unnecessary as 25 I construct these parts with stiffly engaging screws.

The accompanying drawings show instruments made in accordance with my invention.

30 Figure 1 is a side elevation of a resonator with part of the casing and silk gauze removed and Figure 2 is a section on the line 2, 2, Figure 1. Figure 3 is a modification of Figure 1 in which the angle joints are inside the resonator casing. Figure 4 is a front elevation as seen when looking at the face of the wearer and with most of the silk gauze removed and Figure 5 a plan of an instrument consisting of two resonators 40 coupled together.

a is the resonator casing having an elliptical opening closed by silk gauze *b* and within it a tapered tube *c* whose large end is close to the back wall of the casing *a*. To

the back wall of the casing *a* may be secured 45 by a screw *d* a sound reflector *e* of glass. To the smaller end of the tube *c* is secured an angle piece *f* on which is rotatably mounted a second angle piece *g* and on this second angle piece *g* is rotatably mounted an 50 ear tube *h* having an ivory tip *j* for entering the wearer's ear. Set screws *k* and *l* are provided for securing the second angle piece *g* and ear tube *h* in position. The provision of the angle pieces *f* and *g* allows 55 of the adjustment of the ear tube *h* in all directions relatively to the tapering tube *c*. The angle pieces *f* and *g* may be outside the wall of the resonator as shown in Figure 1 or within it as shown in Figure 3. When two 60 resonators *a* are used they are connected together by an adjustable spring coupling *m* which extends over the top of the head, and the resonators *a* are located above and somewhat behind the ears of the wearer, whilst 65 the ivory tips *j* of the tube *h* enter his ears. When a single resonator is used a suitable pad is situated at the other end of the adjustable spring coupling *m*.

What I claim is:—

70

1. An acoustic instrument consisting of a resonator casing, a tapering tube in the casing, an angle piece at the end of the tapering tube, a second angle piece rotatably connected to the first and an ear tube rotatably 75 connected to the second angle piece.

2. An acoustic instrument consisting of a resonator casing, a tapering tube in the casing, an angle piece at the end of the tapering tube, a second angle piece rotatably 80 connected to the first, an ear tube rotatably connected to the second angle piece and set screws for securing the second angle piece and ear tube in position.

In testimony that I claim the foregoing 85 as my invention I have signed my name this 23rd day of June 1921.

CHARLES KAHN.
